INDICATING PLUG FUSE

Frank C. La Mar, New York, N. Y., assignor to
Great Western Fuse Company, New York,
N. Y., a corporation of Delaware

Application March 17, 1932. Serial No. 599,371

3 Claims. (Cl. 200—121)

This invention relates to electrical devices, particularly to thermal fuses for use in connection with electrical circuits, of the form commonly known as a plug fuse, combined with means for indicating the integrity of the fusible element, and more especially to means for preventing a willful misuse of such a combined device.

It is quite universally known that it is necessary to protect electrical circuits by means of devices, such as thermal fuses, which melt or become disintegrated or destroyed when an excessive flow of current passes through the circuit of which the fuse forms a part. An especially well known form of thermal fuse is that known as "plug fuses". Ordinary plug fuses consist, generally, of an insulating body having two terminals on the outside thereof so constructed and arranged as to be readily brought in contact with the terminals of an electrical circuit, by way of what is known usually as a fuse block. These fuses are so universally used, and are made by so many different manufacturers, and must all be usable in practically any of the well known forms of fuse block, that they have become, in truth, standard, so that they may well be referred to as, standard, fuse plugs. At any rate, they are substantially standard as regards their general external dimensions.

Various forms of plug fuses have been made especially for the purpose of enabling one to readily ascertain whether or not the fusible or thermal element is intact. A desirable form for thus ascertaining the integrity of the fusible element is shown, described and claimed in my co-pending application Serial No. 594,024, filed February 19, 1932, and entitled, "Indicating plug fuse".

The combined plug fuse and fusible element integrity indicator of my prior application, above mentioned, includes two spaced readily accessible electrical contacts which if bridged by an electrical conductor, which may readily be done, would then not properly protect the electric circuit in which the plug fuse is inserted.

A principal object of this invention is to provide a combined fuse and fuse integrity indicator, preferably substantially embodying the invention of my prior, above mentioned application but which will include features of construction preventing the willful abuse of the structure in such a way as to substantially destroy its protective function.

Other objects and advantages will appear as the description of the particular physical em-

bodiment selected to illustrate the invention progresses, and the novel features will be particularly pointed out in the appended claims.

In describing the invention in detail and the particular physical embodiment selected to illustrate the invention, reference will be had to the accompanying drawing and the several views thereon, in which like characters of reference designate like parts throughout the several views, and in which:

Figure 1 is a cross-sectional view of a combined plug fuse and fusible element integrity indicator with a structure embodying my invention included therein; Fig. 2 is a cross-sectional view of the device as shown by Fig. 1 but taken on a plane at a right angle to the plane upon which Figure 1 is taken; Fig. 3 is a side elevational view of the device of Fig. 1; Fig. 4 is a top plan view of the device as shown by Fig. 3; Fig. 5 is a top plan view of the device as shown by Fig. 3 but with the cover portion of the indicator removed; Fig. 6 is a top plan view of the device as shown by Fig. 3 but with the integrity indicator removed.

The device includes a body 1 formed of insulating material, preferably a material such as porcelain. The body has an end contact member 2 having an extension 3 projecting into the interior hollow portion 4 of the body. The body is provided with an outer threaded shell contact 5 forming the other side of the electrical circuit. The contact 2 is connected with the shell 5 by means of a thermal fusible element 6. A device embodying the above mentioned parts would be substantially what is known as a plug fuse and would protect a circuit in which it is inserted if shell 5 were connected to one terminal of the circuit and contact 2 to the other terminal.

In order to indicate the integrity of the thermal fusible element 6, applicant provides a contacting portion or prong receiving clip contact 7 intermediate the member 3 and the shell 5 and places an additional conducting member in contact with the member 3 leading to the prong receiving or contacting clip member 9.

By connecting a lamp across the clips or contact members, as 7 and 9, an indicator for the member 6 is produced. In the form shown by applicant, a lamp 10, preferably of a distinctive color indication such as a neon discharge lamp is positioned in a hollow insulating casing 11 having the top member or cover 12 formed with light apertures 13. One terminal 14 of the lamp is connected to a conducting metallic prong 15 and the other terminal 16 of the lamp is connected through a resistance 17, preferably of the

grid leak type, to another conducting metallic prong 18.

- If the prongs 15 and 18 are inserted into the clips 7 and 9, the lamp 10 is connected across the terminals of the fusible element 6. Just so long as the fusible element 6 is intact, sufficient current will not pass through the lamp 10 to cause it to light sufficiently so as to be seen, but if the fusible element becomes disintegrated or 10 "blown", then the prongs 15 and 18 being connected from the shell 5 to the contact 2, sufficient current will pass through such circuit to cause the lamp to glow or light indicating the disruption of the fusible element 6.
- 15 The indicating portion of the device may be entirely removed from the body 1 by a pull upon the body 11. When this has been done, the clips or contact members 7 and 9 are in an exposed or partially exposed condition so that one might 20 willfully place a conducting member in contact with clips 7 and 9 so that the fuse 6, even if in place, would not function as intended, and if the fusible element 6 had been "blown", then the effect of the opening of the circuit would be 25 destroyed because the conductor connecting clips 7 and 9 would directly connect contact 2 with the shell 5.

In order to prevent a dangerous condition which might arise by reason of placing an electrical conductor from the clip 7 to the clip 9, applicant has formed the member 8 as a fusible element. In order to indicate this, applicant has indicated a reduced portion 19, best shown in Fig. 2. This reduced portion 19 is formed of 35 such material and is of such current carrying capacity that if current flows through it in excess of a very small amount, say a slightly greater amount than is necessary to light the lamp 10, then the portion 19 melts and breaks 40 the circuit.

By the use of the supplementary fusible element 19 applicant effectually prevents a dangerous misuse of the plug portion of his combined plug and fuse integrity indicator, because 45 if the fusible element 6 is destroyed and a "jumper" or electrical conductor is connected to and between clips 7 and 9, then upon the passage of the slightest amount of current, that is, a fraction of an ampere, the fusible element 19 included in the member 8 will be destroyed. Of course, the fusing value of the member 19 may 50 be made almost anything desired, the limiting value, of course, being always somewhat higher than the current required to operate the indicator.

In order to separate and protect elements 6 and 8 from undesirably affecting one another, applicant uses the sleeve 20, formed preferably of substantially non-combustible material, such as 60 porcelain.

Although I have particularly described one particular physical embodiment of my invention, and explained the principle, mode of construction, and operation thereof, nevertheless, I desire to have it understood that the form selected is merely illustrative, but does not exhaust the possible physical embodiments of the idea of means underlying my invention.

What I claim as new and desire to secure by Letters Patent of the United States, is:

1. In a plug fuse, in combination: an insulating body; two metallic terminals on the outside of the body adapted for cooperation with the terminals of an electrical circuit to be protected; a thermal element connecting said two first mentioned terminals, two metallic contacts, one electrically connected to one of the first mentioned terminals and adapted to be connected to one terminal of an electrical indicating device, and the other of the two metallic contacts connected to the other of the said first mentioned terminals and including a fusible section of relatively low current carrying capacity, and adapted to be connected with another terminal of an electrical indicating device whereby an electrical connection between the said two metallic contacts will allow only substantially the current needed for the electrical indicating device to operate and a substantially greater current will cause the fusible section to fuse. 100
2. In a system of electrical circuits wherein a plug fuse is used for protection against an excessive flow of current, the combination of additional metallic contacts, electrically connected, one to each terminal of the plug fuse, said contacts adapted for connection to the terminals of a fuse integrity indicating lamp, the inclusion in the circuit of one of the said additional metallic contacts of a fusible section of relatively low current carrying capacity, whereby connection of 110 substantial current carrying capacity between the additional metallic contacts will allow a current of sufficient value to flow and cause the said fusible section to become fused.
3. In a plug fuse, in combination: an insulating hollow body; two terminals on the outside of the body for cooperation with terminals of an electrical circuit to be connected; two conducting members, each connected electrically to one of the terminals, and one including a section of 125 relatively low current carrying capacity; a thermal element of relatively high current carrying capacity connecting said two terminals; said conducting members forming contact terminals for cooperation with the contact terminals of a 130 thermal element integrity indicator.
